United States Patent Office.

GEORGE P. FULLER, OF PHILADELPHIA, PENNSYLVANIA.

Letters Patent No. 90,161, dated May 18, 1869.

IMPROVED RAILWAY-CHAIR

The Schedule referred to in these Letters Patent and making part of the same.

To all whom it may concern:

Be it known that I, GEORGE P. FULLER, of Philadelphia, in the county of Philadelphia, and State of Pennsylvania, have invented a new and useful Improvement in Railroad-Chairs; and I do hereby declare that the following is a full and exact description thereof, reference being had to the accompanying drawings, and to the letters of reference marked thereon.

The nature of my invention consists of a railroad-chair, which has a longitudinal groove in its under side to receive the contiguous ends of two rails, which are notched out on their upper edge, so that when the chair is in place there shall be a tread of the latter in continuation with the tread of the rails, the chair having vertical-slotted wings through which a plate-key is passed and tightened by means of a vertical spring-key, the said plate-key coming beneath the chair and the ends of the rails, and the chair being also provided with flanges on each side of the vertical wings, which are bolted to cross-ties in the usual manner.

The construction and arrangement of the improved chair with the rails will be understood by the following description.

In the accompanying drawings—

Figure 1 is a plan of the improved chair in connection with two rails.

Figure 2 is a cross-section of the same at the line xx of fig. 1.

Figure 3 is an isometrical view of the key E.

Like letters in all the figures indicate the same parts.

A is the improved chair, and

B B, the contiguous ends of two rails.

C C are cross-ties, to which the rails and chair are confined.

The chair A has a longitudinal groove, a , throughout its whole length, which fits over the projections

$b b$ of the rails B B, which are formed by notching out the ends of the same equal in depth to the thickness of the metal of the chair, so that when the latter and the rails are in connection, there shall be an even and continuous tread.

The chair has vertical wings D D, which have horizontal slots, c , to receive the key E, by means of which the chair and rails are firmly held together.

I usually make the chair of wrought-iron, and form the wings D D, by making slits, 1 2, equal to the depth of the wings, and bending them perpendicular to the base d , at the same operation in which I bring the other parts of the chair into the finished form.

The key E, which is represented in detail in fig. 3, has holes e in two rows, alternating with each other to give greater accuracy in the tightening of the parts, the variations of the degrees of tightness being less in changing the spring-key F from one row to the other than it would be with only a single row, in consequence of this arrangement.

The chair is confined to the cross-ties C by means of the spikes f , which pass through the flanges G G G G.

What I claim as my invention, and desire to secure by Letters Patent, is—

The combination and arrangement of the railroad-chair A, having a slot, a , vertical wings D, and flanges G, the plate-key E, and spring-key F, with the rails B, substantially as described.

In testimony that the above is my invention, I have hereunto set my hand and affixed my seal, this 23d day of July, 1868.

GEORGE P. FULLER. [L. S.]
